AUTOMATIC CONTROL VALVE FOR CONDENSER COOLANT

Filed Feb. 12, 1947

UNITED STATES PATENT OFFICE

2,551,758

AUTOMATIC CONTROL VALVE FOR
CONDENSER COOLANT

Alwin B. Newton, Dayton, Ohio, assignor to
Chrysler Corporation, Highland Park, Mich., a
corporation of Delaware

Application February 12, 1947, Serial No. 727,963

5 Claims. (Cl. 236—92)

1

This invention relates to apparatus for controlling the admission of cooling liquid to the condenser of a refrigerating system.

The invention to be described herein may be used in conjunction with a system employing a circulating liquid to cool the condenser or in conjunction with a system combining air circulation with moisture evaporation as the cooling mediums.

In either of the above systems it is desirable to meter the supply of liquid which will herein-after be referred to as water, to the condenser. As the heat absorption of the system becomes greater, the temperature of the refrigerant in the condenser and the requirement for cooling water increase. Since the refrigerant temperature is reflected in the refrigerant pressure, a pressure responsive apparatus is provided to control the admission of cooling water to the condenser. I have found that to assure the circulation of the optimum quantity of water the apparatus should, in addition, be responsive to the pressure of the cooling water which is furnished by the apparatus to the condenser. The higher the water pressure the greater should be the restriction to its flow provided by the apparatus.

A further object of the invention is to provide an apparatus capable of preventing the water from flowing at a rate above a predetermined desirable maximum rate regardless of the pressure of the refrigerant or the water pressure.

It is also an object of the invention to provide apparatus adapted to automatically initiate the flow of cooling water when the refrigerant pressure becomes sufficiently great.

An additional object of the invention is to provide an apparatus adapted to regulate the quantity of water admitted to the refrigerating condenser in response to changes in the temperature of the water.

A manual means for adjusting the apparatus to vary the maximum rate of water flow referred to above is provided.

In the drawings:

Fig. 1 illustrates one form of the control apparatus showing its use in conjunction with a refrigerating system employing a water-cooled condenser; and

Fig. 2 illustrates a slightly modified form of control apparatus showing its use in conjunction with a refrigerating system employing a condenser cooled by air and the evaporation of moisture.

In Fig. 1 a refrigerating system employing a water-cooled condenser is illustrated. The sys-

2

tem includes a compressor 10, a condenser 12 and an evaporator 14. A header 16 is connected to the compressor by a tube 18 and to the inlet portion of the condenser by a tube 20. A liquid receiver 22 is connected to the outlet portion of the condenser 12. A tube 24 operatively connects a liquid receiver 22 and the evaporator 14. A tube 26 connects the evaporator 14 with the compressor 10. The refrigerant is thus compressed in the compressor 10 and passes through the tubes 18 and 20 to the condenser 12 where it is liquefied. The liquefied refrigerant passes through liquid receiver 22 and tube 24 into the evaporator 14 from which it is returned to the compressor by the tube 26 in the usual manner. An expansion valve 28 is interposed in the tube 24 upstream from the evaporator. The expansion valve 28 is controlled by a heat bulb 32 on the suction line 26 leading to the compressor 10. The system thus far described is intended to be a conventional refrigerating system and has been diagrammatically illustrated. The invention relates particularly to the means by which the condenser 12 is cooled.

The condenser 12 as illustrated in Fig. 1 is cooled by the passage of water through the coil 34 positioned within the condenser 12. The outlet 36 of the coil 34 may be connected by any suitable means, not shown, to a drain to dispose of the water. The inlet tube 38 of the coil 34 is connected to a valve generally designated by the numeral 40.

The valve 40 is provided with an inlet 42 connected to a suitable source of water supply. The valve is provided with a housing 44 of generally cylindrical shape having a valve seat 46 positioned in the housing 44 in operative relation to inlet 42. The inlet 42 is preferably located on the bottom of the valve. The tube 38 which comprises the water outlet from the valve is preferably positioned about midway up the side of the cylinder. The opening 43 in the housing 44 for the inlet of water is preferably of greater diameter than the opening 39 in the housing for the outlet of water. Water pressure is thus built up within housing 44 when there is insufficient restriction of opening 43 by mechanism to be described. The upper portion of the housing 44 is connected by a tube 48 to the header 16. This serves as an inlet for refrigerant. A valve stem 50 having a valve head 52 is adapted to cooperate with the valve seat 46 to restrict the flow of water through the inlet opening 43. The housing 44 is provided with internal threads adapted to support a threaded annular flange member 54 in the lower portion of the housing. The flanged mem-

ber 54 serves as a seat for one end of a vertically positioned coil spring 56. The upper end of the spring 56 supports a disc 58. The disc 58 is substantially flat with the exception of an upwardly extending portion 60. A diaphragm 62 is positioned normal to the axis of the housing and in the upper portion thereof in abutting relationship with the top of the portion 60 of diaphragm 62. Refrigerant entering the valve housing by means of the tube 48 imparts a downwardly directed force on the diaphragm 62 as an incident to the pressure existing in the refrigerating system between the compressor 10 and condenser 12. It will thus be seen that movement of the diaphragm 62 is imparted to the spring 56 causing a contraction thereof. The diaphragm 62 may be suitably secured to the walls of the housing 44 so that the refrigerant cannot leak by the diaphragm.

A flexible metallic bellows 64 is concentrically positioned within the housing 44 and has its upper portion secured to the disc 58. The lower portion of the bellows is secured to a second disc 66. The valve stem 59 previously referred to is secured to the disc 66. A coil spring 68 is positioned between the discs 58 and 66 and resists any tendency for the bellows 64 to be compressed. Suitable cooperating cup elements 70 and 72 are provided for operation in conjunction with the spring 68. Cup element 70 is secured to the disc 66. Cup element 72 is secured to the disc 58. The cups are provided with cooperating lip portions 74 which freely permit the cups to be telescoped together but resist any tendency for the bellows 64 to expand beyond a predetermined limit established by the lips 74.

In the lower portion of the device the valve head 52 is normally seated upon the valve seat 46 by the spring 56 thus interrupting the flow of water to the condenser. When the refrigerating system is operated and the pressure of the refrigerant in tube 48 exceeds a predetermined value, the diaphragm 62 is forced downwardly and the valve head 52 moved away from the valve seat 46. Water is thus permitted to enter the housing 44 from the inlet 42 and to enter the condenser 12 through the connecting tube 38. It should be noted that the amount of water admitted is dependent upon the amount of deflection of the diaphragm 62. Thus the apparatus is adapted to determine that the flow of water shall begin when a sufficient refrigerant pressure is obtained. During operation when the temperature of the refrigerant in the condenser increases it is accompanied by an increase of pressure. The increased pressure operates through the valve 40 to increase the supply of water to the condenser 12 to combat the high temperature.

The valve 40 is in addition responsive to water pressure and although the valve operates as described above to increase the flow of water as the pressure of the refrigerant increases, the valve itself establishes limits to this action. It is preferable that a predetermined maximum flow of water be established. This will be referred to hereinafter as the optimum rate. When the diaphragm 62 has been deflected to open the valve 52 and water is admitted to the valve housing, the pressure of the water in the inlet 43 as reduced by the escape of water through the outlet 39 reacts upon the discs 58 and 66 tending to compress the bellows 64. This tendency is resisted by the spring 68. The pressure behind the water attempting to enter the outlet tube 38 ef-

fects its velocity and therefore its rate of flow and cooling effect upon the condenser 12. Thus as the pressure builds up within the housing 44 the need for additional water to enter through inlet 43 is reduced and the compression of the bellows 64 accordingly closes the valve 52. There is thus established an optimum rate of flow of water in tube 38 which will never be exceeded regardless of the pressure of the refrigerant in tube 48. If the refrigerant pressure becomes excessive and opens the valve 52 the great amount of water attempting to enter the housing compared to what may leave through restricted opening 39 builds up a water pressure which tends to close the valve.

The bellows 64 can be evacuated and the collapsing pressure determined entirely by the spring 64. However, in the preferred construction the bellows may be filled with a volatile material such as one of the Freons which is responsive to the temperature of the water passing through the housing. A typical one of the Freons which would be suitable is Freon-12, the chemical formula of which is CCl_2F_2 . When the water temperature goes up the gas expands and increases the resistance to a collapsing of the bellows 64. Thus when warm water is provided, a great quantity of water should pass through the condenser in a unit time to effect a cooling thereof and the expansion of the gas in the bellows automatically makes this adjustment. The lips 74, previously described, limit the extension of the bellows in response to expansion of the gas.

A means is provided by which the valve may be manually adjusted to vary the optimum rate to suit individual conditions. The flanged member 54 is provided with internal radial teeth 76. An elongated pinion 78 is adapted to mesh with the teeth 76. Rotation of the pinion drives the flanged member 54 causing it to rotate and be lifted by reason of its threaded engagement with the housing 44. A shaft 80 is connected to the pinion 78 and is rotatably mounted in the housing 44. The shaft may be provided with a squared end adapted to receive a wrench or other tool for rotation thereof. Suitable packing 82 retained in a collar 83 by a packing gland 84 may be provided to prevent the leakage of water out of the housing around the shaft. A cap 85 may be removably secured over the collar 83 to cover the end of the shaft 80 when not in use.

In Fig. 2 the novel valve is illustrated as being used in conjunction with a different type of refrigerating system. The same valve is interchangeable with either system. The system in Fig. 2 comprises a compressor 110, a condenser 112 and an evaporator 114. The system is the same as that described with reference to Fig. 1 except that a different type of condenser has been substituted. The condenser 112 is cooled by air and the evaporation of moisture. A blower 116 is positioned with its axis perpendicular to the condenser 112 and is adapted to blow air therethrough. The blower is preferably an electric fan supplied with current from power lines 118 and 120. Power line 120 is illustrated as having a pressure switch 122 therein. The switch 122 is controlled by a diaphragm motor of any usual type (not shown) subjected to the refrigerant pressure on the inlet side of the condenser by means of a tube 124 communicating with the refrigerating system. The condenser blower will thus operate whenever the pressure

of the refrigerant in the condenser rises above a predetermined value indicating that the need for condensing action exists. The cooling action of air is supplemented by the evaporation of moisture from the surfaces of the condenser coil. The means for creating a spray of water which contacts the condenser and is evaporated therefrom comprises a cup-shaped hub 126 secured to the blower. The open side of the cup faces the condenser. A tube 138 is connected to the outlet side of the novel valve previously described and supplies water to the interior of the cup. The water projected into the cup is thrown from the lip and is sprayed over the condenser by the action of the blower. Other types of spraying means may be substituted if desired. The evaporation of the water from the coils of the condenser increases the cooling of the condenser.

The valve 40 described with reference to Fig. 1 may be used in this system if desired and would regulate the supply of water to the blower. In Fig. 2, however, a modified form of valve has been illustrated. The modified form is substantially the same as that described with reference to Fig. 1 with the exception that a different manual adjustment is provided. A gear 144 is rotatably mounted on the base of the housing 140 and is positioned by a collar 143 secured to the base of housing 140 coaxially with the valve stem 50. A threaded collar 146 is secured to the gear 144. A threaded flanged member 148 is positioned in threaded engagement with the collar 146. The flanged member 148 supports a spring 56' which is similar to the spring 56 of Fig. 1. The flanged member 148 is preferably provided with an opening 149. A pin 151 is secured to the housing and extends vertically through the opening 149 to prevent rotation of the member 148 relative to the housing.

A shaft 150 penetrates the side wall of the valve housing 140 and has a gear 152 secured to the end thereof in operative engagement with the gear 144. A packing member 154 is secured to the exterior wall of the housing and is penetrated by the shaft 150. Suitable packing 156 in combination with a packing gland 157 seals the shaft in the member 154. The shaft 150 may be provided with a squared end 158 adapted to cooperate with a wrench or other tool for rotation of the shaft 150. Rotation of the shaft 150 and gear 152 rotates the gear 144 and collar 146, thereby causing relative axial movement between the collar 146 and flanged member 148. This changes the effective length of the spring 56. The usual cap 160 may be removably secured to the packing member 154 when the adjusting mechanism is not in use.

I claim:

1. In a refrigerating system of the compressor-condenser-expander type, a valve for controlling flow of a condenser cooling liquid, said valve comprising a housing having inlet and outlet openings therein and an element movable relative to said housing to close said inlet opening, a spring biased to move said element to closing position, a device subjected to refrigerant pressure and adapted to compress said spring to open said valve to an extent varying in direct relation to the refrigerant pressure in the condenser and a collapsible bellows interposed between said element and said device, subjected to the pressure of the cooling liquid and tending to move said element to vary the opening of said valve inversely with respect to the cooling liquid pressure in said housing, a first means associated

with said bellows and adapted to yieldably oppose the collapsing of said bellows and a second means associated with said bellows and adapted to establish a limit for the extension of said bellows.

2. In a refrigerating system having a condenser for a refrigerant, means including a valve for regulating a supply of cooling liquid to said condenser, said valve comprising a housing and a movable element, said housing having a liquid inlet opening and an outlet opening connected to a source of liquid and said condenser respectively, said housing having a valve seat associated therewith between said inlet opening and said outlet opening, said element being mounted in said housing for movement relative to said valve seat to regulate the flow of cooling liquid past said valve seat and through said housing, a spring biased to move said element on to said valve seat, a first device in said housing which is responsive to the pressure of refrigerant in said system and adapted to move said element away from said valve seat and toward its open position in response to increase in pressure of said refrigerant and a second device interposed between said valve seat and said outlet opening, subjected to the outlet pressure of the cooling liquid in said housing and tending to move said element on to said valve seat toward its closed position as the pressure of the cooling liquid in said housing downstream of said valve seat increases, a first means associated with said second device and operable to yieldably oppose the movement of said element toward its closed position on said valve seat under the influence of said second device and a second means associated with said second device and adapted to limit the movement of said second device in a direction tending to move said element off said valve seat toward its open position.

3. In a refrigerating system having a condenser for a refrigerant, means including a valve for regulating a supply of cooling liquid to said condenser, said valve comprising a housing and a movable element, said housing having a liquid inlet opening and an outlet opening connected to a source of liquid and said condenser respectively, said housing having a valve seat associated therewith between said inlet opening and said outlet opening, said element being mounted in said housing for movement relative to said valve seat to open and close said valve, a spring biased to move said element to its closed position, a first device in said housing which is responsive to the pressure of refrigerant to said system and adapted to move said element toward its open position in response to increase in pressure of said refrigerant and a second device interposed between said valve seat and said outlet opening, subjected to the pressure of the cooling liquid in said housing downstream of said valve seat and tending to move said element toward its closed position as the pressure of the cooling liquid in said housing increases, a first means responsive to the temperature of the cooling liquid and adapted to move said element in a first direction toward its open position in response to an increase in the temperature of said cooling liquid and a second means associated with said first means and adapted to limit said first means in its movement of said element in said first direction.

4. A control apparatus for regulating a supply of coolant to the condenser of a refrigerating system comprising a housing having an inlet open-

ing and an outlet opening for coolant, a valve movable between open and closed limits and operable to regulate the flow of coolant through said inlet opening, first means mounted for movement and adapted to be connected to a source of refrigerant in said system for movement in response to variations in the pressure of refrigerant in the system, a spring mounted to urge said valve toward its open limit, said spring operatively connecting said first means and said valve to move said valve in response to movement of said first means and means exposed to the pressure of the coolant and operatively connected to the spring to facilitate distortion of said spring in response to increase in the pressure of coolant in said housing downstream of said valve to thereby move said valve toward its closed limit in response to increase in coolant pressure.

5. A control apparatus for regulating a supply of coolant to the condenser of a refrigerating system comprising a housing having an inlet opening and an outlet opening for coolant, a valve movable between open and closed limits and operable to regulate the flow of coolant through said inlet opening, a movable element defining a compartment within said housing, said housing having an opening from said compartment adapted to be connected to a source of refrigerant in said system in order that said element may be moved in response to variations in the pressure of refrigerant in said compartment, a first spring carried within said housing and engaging said

10

15
